JASPER VAN WORMER AND MICHAEL McGARVEY, OF ALBANY,
NEW YORK.

Letters Patent No. 84,024, dated November 10, 1868.

MAGAZINE IN BASE-BURNING STOVES.

The Schedule referred to in these Letters Patent and making part of the same:

To all whom it may concern:

Be it known that we, JASPER VAN WORMER and MICHAEL McGARVEY, both of the city of Albany, in the county of Albany, and State of New York, have invented a new and useful Improvement in Magazines for Self-Feeding Stoves; and we do hereby declare that the following is a full and exact description thereof, reference being had to the annexed drawings, making a part of this specification, in which—

Figure 1 is a sectional view of a complete stove having our improved magazine or feeder.

Figure 2 is a perspective view of the magazine or feeder.

Figure 3 shows our method of hanging the feeder in the stove, so that it may be adjusted to regulate the discharge of the coal.

Figure 4 represents our method of connecting the two parts of the feeder, *i. e.*, the reservoir and the neck.

Like letters refer to like parts.

A is the coal-reservoir, having its lower part, C, contracted.

B is the neck, having a flaring mouth-piece, D, attached to its upper end.

E are pins, attached to the outside of the flaring mouth-piece D.

F are notches in the lower edge of the contracted end, C, of the reservoir.

I, fig. 4, is the portion of this lower edge between the notches, cut on an incline.

The dotted line H H, fig. 4, is the upper edge of the flaring mouth-piece D, as it rests on the inside of the contracted end, C.

In self-feeding or magazine-stoves, as heretofore constructed, there have been found several serious objections, arising from the peculiar construction of the reservoir.

When the reservoir has been made of the same size throughout its entire length, or where there has been a slight gradual increase in size towards the lower end, it is found that the coal in the reservoir presses down on the burning mass of coal underneath with too great weight.

When the reservoir is constructed with a contracted discharge-end, the coal is continually choking and clogging up at the outlet, so that its descent is not free, often clogging during the night, causing the fire to go out for the want of a supply of fuel. The most tangible reason for this obstruction is that the heat enters the coal at the lower end of the reservoir, where it lies immediately over the burning mass in the fire-pot, causing the coal to become expanded, and bind itself fast, forming an arch, so that a poker of iron bar has to be used to force it down into the fire-pot.

To obviate and overcome these difficulties, we construct a magazine or feeder as follows:

The upper portion A consists of a reservoir, made large, so as to hold a large body of coal, and having its lower portion contracted, as shown in the drawings.

Attached to this reservoir, and forming the lower part of the feeder, is a neck, B, of sufficient length that the reservoir, with the body of coal in reserve, shall be placed at such a distance from the burning coal as to be out of the intense heat. This neck is enlarged at its lower end, giving a free discharge of the coal, with no risk of clogging or choking. The enlarging of the neck at its lower end will completely break up the arching or clogging-up of the coal. The enlargement of the neck is by a uniform and regular increase or flaring from the upper to the lower end, giving the neck a conical shape.

The neck may be joined on to the reservoir, and permanently fastened to it, but our method of connecting the two is as follows:

The sides of the reservoir, at their lower part, are contracted at a very decided and perceptible angle. Attached to the upper end of the neck is a flaring mouth-piece, formed at an angle to correspond with that of the contracted part of the reservoir. The diameter of the upper part of the mouth-piece must be greater than that of the lower edge of the contracted end of the reservoir, so that, while the mouth-piece will fit down into this contracted end, it will not slip entirely through it, but will be supported by it. In the lower edge of the contracted end of the reservoir are cut three notches, of the same size, and at a uniform distance apart. Three pins are attached to the outside of the flaring mouth-piece of the neck, so as to correspond with these notches, and to allow of their passing down through the notches. The lower edge of the contracted end of the reservoir, between each of these notches, is cut on an incline, so that, when the neck has been passed down through the reservoir, the pins passing through the notches, the flaring mouth-piece of the neck resting upon the inside of the contracted end of the reservoir, by a slight turn of the neck, the pins pass under the inclined edge, and lock the neck and reservoir firmly together.

What we claim as our invention, and desire to secure by Letters Patent, is—

1. Attaching to the ordinary contracted reservoir a neck, having its lower end enlarged, substantially as and for the purpose described.

2. The method of attaching the neck to the reservoir, substantially as set forth.

JASPER VAN WORMER.
MICHAEL McGARVEY.
